(57) CLAIM

The ornamental design for the “vehicle wheel,” as shown and described.

DESCRIPTION

FIG. 1 is a perspective view of the vehicle wheel showing my new design;

FIG. 2 is a front elevational view thereof; and,
FIG. 3 is a cross-sectional view taken along the lines of 3—3 of FIG. 2.

The broken line showing of environment is for illustrative purposes only and forms no part of the claimed design.
